THOMAS CARMICHAEL, OF NEWARK, NEW JERSEY.

Design No. 4,840, dated April 25, 1871.

DESIGN FOR MOSQUITO-NETTING.

The Schedule referred to in these Letters Patent and making part of the same.

I, THOMAS CARMICHAEL, of the city of Newark, County of Essex and State of New Jersey, have invented and produced a new and original Design for Mosquito-Netting, of which the following is a specification.

The design will be understood by tracing the course of the two threads marked B and C in the drawing. The thread B is formed first into a loop, *a*, in the row D, as in ordinary knitting, and passing on to the row E lies loosely or unlooped behind the loop *b*, formed from the thread C, below and in front of a corresponding loop, *b*, formed from the thread C above.

The thread C lies loosely or unlooped behind the loop *a*, formed by succeeding thread B in the row D; and in front of a corresponding one formed in the thread B preceding, and passing on to the next row is formed into a loop, *b*, which confines the unlooped portion of the thread B, first described.

Thus it will be seen that the thread B is only formed into loops in the row D and lies loosely between the loops in the row E, and that the thread C is only formed into loops in the row E and lies loosely between the loops in the row D, the resulting figure being a diamond with a single loop crossing it at the center.

It will be seen from this description that the figure can be readily distinguished from that shown in the patent of Thomas Crane, of June 15, 1869, and which is expressly disclaimed.

Claim.

The design for mosquito-netting, as herein shown and described.

THOS. CARMICHAEL.
